PHOTOTUBE HOUSING WITH SELECTABLE FILTERS

Monroe Hamilton Sweet, Binghamton, N. Y., assignor to General Aniline & Film Corporation, New York, N. Y., a corporation of Delaware

Application September 17, 1948, Serial No. 49,754

6 Claims. (Cl. 250—239)

1

This invention relates to photographic apparatus and more particularly to a housing for phototubes accommodating a series of selectable filters.

In photo-electric devices it is often necessary to employ various types of filters between the light source and the tube. In certain applications, for example, in densitometers which measure the relative density of color positives, filters of different colors are used which must be placed between the photocell and the specimen in order to determine the absorption characteristics of the material at various wave lengths.

Filters of this type have heretofore been used manually or placed on a flat disc which revolved thus permitting selected insertion of the filters. This type of construction has the disadvantage that when high densities are encountered, stray light entering the device is apt to cause a large error in the indication.

Particularly in photo-electric tube circuits which employ a multiplier type phototube resulting in a high degree of amplification, it is extremely important to have the tube completely shielded from light as well as electrostatic effects. The housing of such phototubes must have a light-tight construction and must offer also good electrical shielding.

A particular feature of this invention is the novel construction of housing for phototubes which excludes light completely and at the same time incorporates means for selectively inserting a series of filters without the danger of stray light entering the phototube.

A particular advantage of the structure in accordance with this invention is the compactness of assembly which includes the filter holder within the phototube housing and permits the selection with ease of the particular filter desired from outside of the housing.

Another advantage of the invention resides in the means for excluding stray light completely between the filter and the phototube as well as between the housing and the filter.

Other features and advantages will be apparent from the following description of the invention, pointed out in particularity in the appended claims and taken in connection with the accompanying drawing in which:

Fig. 1 is a sectional view of the housing, showing the filter holder therein, and;

Fig. 2 is a cross sectional view of the complete housing along the lines 2—2 of Fig. 1.

Referring to the figures, the phototube housing comprises a U-shaped casing 3 which may be of cast aluminum or other suitable metal. The bot-

2

tom part of the casing is recessed to accommodate a flat bottom plate 4. In the figures only the part of the phototube housing is shown which incorporates the improvements to which this invention is directed. The rest of the structure may have any desired shape depending upon the particular use to which the photocell is employed. For example, in a densitometer device the housing may terminate in a hinged portion pivoted in a suitable holder whereby it may be lifted up in order to place a specimen on the table on which the plate 4 of the housing may normally rest. This type of housing construction is described and illustrated in Electronics Magazine (November 1946, pages 105-109) in connection with a densitometer instrument designed by the originator of this invention.

The bottom plate 4 has an aperture accommodating a grommet 5, which is of resilient material such as rubber and extends into the space between the inner wall of the bottom plate 4 and the rotatable sleeve 6, the purpose of which will be apparent upon further consideration of the structure. The sleeve 6 is of a cylindrical shape and hollow. At one end it is closed and a shaft extends therefrom through the front portion of the casing 3 in which it revolves in a bearing 8. The end of the shaft 7 carries a knob 9 for rotation by hand of the sleeve 6. This knob may have a knurled surface and engage a pin 10 so as to prevent accidental rotation of the sleeve 6 after a selected position.

The cylindrical side of the sleeve 6 has a series of circumferentially distributed apertures each of which forms a holder for a filter 12 which cooperates with the aperture formed by the grommet 5. It is to be noted that the latter extends in close proximity to the filter holding portion of the sleeve 6. The reason for this is to form a light-tight coupling between the sleeve and the aperture in the wall of the housing formed by the bottom plate 4. In this manner stray light is excluded which otherwise could easily enter the aperture and, as mentioned before, would adversely affect the accuracy of the instrument when high densities are encountered.

Inside the casing 3 and affixed thereto in a flexible band 13 the circumferential length of which is adjustable by means of the screw 14. The purpose of this band is to hold a phototube 15 in position within the housing and it is so dimensioned as to fit over the base 16. In this manner the tube 15 can easily be positioned to have its photo-active element in proper alignment with the aperture in the plate 4. When the band 13 is loose

the tube 15 can be rotated as well as moved axially until proper alignment is obtained. With the screw tightened the band 13 will securely hold the base 16. A socket for the phototube may also be accommodated in the rest of the housing, not shown, together with other circuit components which require careful shielding, depending on the over-all size of the housing chosen to satisfy a particular type of apparatus.

From the above description it is clearly seen that in any position of the housing one of a series of filters may instantly be interposed by simply turning the knob 9. This in no way interferes with the sample through which light intensity is made to energize the phototube and stray light cannot enter the active element of the tube no matter what position the housing may be or what particular filter is being used. The rotating sleeve 6, aside from carrying the filters 12 provides additional shielding and protection for the phototube 15 and adds to the necessary increased weight which is desirable at this end of the housing inasmuch as it usually rests on a sample the surface of which is to be explored.

While only one embodiment of the invention has been disclosed, it is to be understood that the inventive concept may be carried out a number of ways. This application is, therefore, not to be limited to the precise details described but is intended to cover all variations and modifications thereof falling within the spirit of the invention and the scope of the claims.

I claim:

1. In combination a photo-electric tube, a housing for said tube providing complete shielding from outside light, a wall for said housing defining an aperture, the photoactive element of said tube being aligned with said aperture, means for inserting a filter between said tube and said aperture comprising a sleeve rotatable over the tube having a plurality of receptacles each accommodating a filter, and means outside of said housing for rotating said sleeve whereby a desired filter may be interposed between the tube and the aperture in said housing.

2. In combination a photo-electric tube, a housing for said tube providing complete shielding from outside light, a wall for said housing defining an aperture, the photoactive element of said tube being aligned with said aperture, means for inserting a desired color filter between said tube and said aperture comprising a cylindrical sleeve rotatable over the tube having a plurality of circumferentially arranged receptacles in the wall of said sleeve each accommodating a filter and means outside of said housing for rotating said sleeve whereby a desired filter may be interposed between the tube and the aperture in said housing.

3. In combination a photo-electric tube, an elongated housing for said tube having a front portion and side walls providing complete shielding from outside light, one of said walls of said housing defining an aperture, the photoactive

element of said tube being aligned with said aperture, means for inserting a desired color filter between said tube and said aperture comprising a cylindrical sleeve rotatable over the tube having a plurality of circumferentially disposed filters in the wall of said sleeve, means outside of said housing for rotating said sleeve comprising a shaft extending from said portion and journaled therein and a knob on said shaft whereby a desired filter may be interposed between said tube and said aperture.

4. In combination a photo-electric tube, a housing for said tube providing complete shielding from outside light, a wall for said housing defining an aperture, the photoactive element of said tube being aligned with said aperture, means for inserting a filter between said tube and said aperture comprising a sleeve rotatable over the tube having a plurality of receptacles each accommodating a filter and means outside of said housing for rotating said sleeve and means for excluding stray light from entering the space between said aperture and said sleeve.

5. In combination a photo-electric tube, a housing for said tube providing complete shielding from outside light, a wall for said housing defining an aperture, the photoactive element of said tube being aligned with said aperture, means for inserting a filter between said tube and said aperture comprising a sleeve rotatable over the tube having a plurality of receptacles each accommodating a filter and means outside of said housing for rotating said sleeve and means for excluding stray light from entering the space between said aperture and said sleeve comprising a resilient grommet surrounding the aperture defining edges of said wall and extending to the outer peripheral surface of said sleeve.

6. In combination, a photo-electric tube of elongated construction, a housing for said tube comprising a U-shaped cover portion and a flat portion having an aperture extending between the legs of said U-shaped cover, and a front wall accommodating a shaft extending therethrough axially of said tube, a cylindrical sleeve affixed to said shaft inside said housing and a knob affixed to said shaft outside said housing whereby said sleeve may be rotated, the wall of said cylindrical sleeve defining a series of concentrically arranged apertures each accommodating a filter, an adjustable flexible band for holding said tube secured to the inner wall of said housing and circumferentially enveloping the base of said tube permitting longitudinal as well as rotary displacement thereof for proper location of the light sensitive element with said aperture and a resilient grommet surrounding the aperture defining edges of said flat portion and extending in close proximity to the filter holding portion of said sleeve.
